(57) **CLAIM**

The ornamental design of an engine for brush cutter, as shown and described.

DESCRIPTION

FIG. 1 is a front view of an engine for brush cutter according to my new and ornamental design,

FIG. 2 is a rear view thereof,

FIG. 3 is a top plan view thereof,

FIG. 4 is a bottom plan view thereof,

FIG. 5 is a right side view thereof,

FIG. 6 is a left side view thereof,

FIG. 7 is a first perspective view thereof; and,

FIG. 8 is a second perspective view thereof.

The broken lines shown in the drawings are for the purpose of illustrating portions of the article that form no part of the claimed design.
